UNITED STATES PATENT OFFICE

106,683

DESIGN FOR A RACK FOR MAGAZINES OR THE LIKE

Fred D. Farr, Mamaroneck, N. Y., assignor to
Revere Copper and Brass Incorporated, Rome,
N. Y., a corporation of Maryland

Application August 27, 1935, Serial No. 58,322

Term of patent 14 years

To all whom it may concern:

Be it known that I, Fred D. Farr, a citizen of the United States and a resident of Mamaroneck, county of Westchester, State of New York, have invented a new, original, and ornamental Design for a Rack for Magazines or the like, of which the following is a specification, reference being had to the accompanying drawings, forming part thereof.

In the drawings:—

Figure 1 is a perspective view of the rack, showing my design;

Fig. 2 is a side elevational view thereof; and

Fig. 3 is an end elevational view thereof.

The characteristic feature of my design resides in a central upwardly extending abutment member and a pair of opposed scroll-like spring members at opposite sides thereof, with auxiliary scroll-like spring members adjacent the bases of the scroll-like spring members substantially as shown.

I claim:—

The ornamental design for a rack for magazines or the like, substantially as shown and described.

FRED D. FARR.
